US0D1088106S

(12) United States Design Patent (10) Patent No.: US D1,088,106 S
(45) Date of Patent: * Aug. 12, 2025

(54) SOUND BOWL COVER

(71) Applicant: HARMONIC COVERS LLC,
Sheridan, WY (US)

(72) Inventor: Barbara G. Kramer, West Hollywood,
CA (US)

(73) Assignee: HARMONIC COVERS LLC,
Sheridan, WY (US)

() Term: 15 Years

(21) Appl. No.: 29/915,810

(22) Filed: Nov. 3, 2023

(51) LOC (15) Cl. 17-99

(52) U.S. Cl.

USPC D17/99

(58) Field of Classification Search

USPC D17/20, 99; D3/204
CPC G10D 3/00; G10D 13/10; A45C 13/002;
A45C 11/001
